(57) **CLAIM**

The ornamental design for a hockey puck with stakes and vents, as shown and described.

DESCRIPTION

FIG. 1 is a perspective view of a puck with stakes and vents according to the invention;

FIG. 2 is an elevational view of the front and left side of FIG. 1; and corresponds to the lower left or upper right sides of FIG. 3; and,

FIG. 3 is a top plan view thereof, the bottom plan view appearing the same.
